UNITED STATES PATENT OFFICE.

ELIZUR RAYMOND GOODRICH, OF ROSELLE PARK, NEW JERSEY, ASSIGNOR TO
WHEELER CONDENSER & ENGINEERING COMPANY, OF CARTERET, NEW JERSEY.

CONDENSING APPARATUS.

Application filed April 7, 1921. Serial No. 459,266.

To all whom it may concern:

Be it known that I, ELIZUR RAYMOND GOODRICH, a citizen of the United States, residing at Roselle Park, in the county of Union, in the State of New Jersey, have invented an Improvement in Condensing Apparatus, of which the following is a specification.

This invention relates to a part of a steam condensing apparatus and more especially to an apparatus employed in conjunction with a steam condensing system in which the apparatus is used as an ejector pump, such for example as shown and described in the Patent No. 968,926, granted August 30, 1910, to Fischer. This patent discloses an ejector pump or compressor in which the steam and air or other gas is moved by the steam from an ejector nozzle in successive stages and the steam is condensed or separated from the gas between each stage of the operation whether it be compressing the gas or otherwise. The particular object of my present invention is the provision of an apparatus to be used in a steam condensing system in which the condensate is carried to and heated in a primary heater or inter-condenser to the temperature of the vacuum therein and then is conveyed to and further heated in a secondary heater by the exhaust from the steam ejector or ejectors employed, as will be hereinafter more particularly described.

In the drawing:

Figure 1 is a central longitudinal cross section of an apparatus embodying my present invention.

Fig. 2 is a side elevation of the same.

Fig. 2^a is an elevation of the inner face of the water bonnet 19.

Fig. 2^b is a similar view of the water bonnet 18.

Fig. 2^c is a central vertical section of the left hand end of the apparatus as shown in Fig. 2.

Fig. 3 is a central longitudinal cross section and partial elevation of another form of the apparatus.

Fig. 4 is a side elevation of the form of apparatus shown in Fig. 3.

Fig. 4^a is a central vertical section at the left end of the apparatus, and

Fig. 4^b is a similar section at the right end of the apparatus as shown in Fig. 4.

Referring to the drawing and first par-

ticularly to Figs. 1 and 2, the apparatus comprising this invention may include a substantially cylindrical shell or body member 10, having in the sides thereof in suitable positions, flanged bosses 11 and 12. Interiorly this body member is provided with a partition wall 13 which extends from the top thereof to a line an appreciable distance from the bottom thereof, dividing the interior of the shell into compartments with one of which an opening in the wall of the shell surrounded by the boss 11 communicates, while an opening in the shell surrounded by the boss 12 communicates with the other compartment. In a suitable position in the bottom of the shell, the same is provided with a tap 14 to which a drain pipe 15 is connected. The opposite ends of the tubular shell are flanged as plainly indicated in the drawing and against which tube plates 16 and 17 are adapted to lie and be connected. At one end and against the tube plate 16, a water jacket or bonnet 18 is secured, while at the opposite end a water jacket or bonnet 19 is likewise secured, the parts being connected in any suitable manner. Within the shell and substantially filling the compartment A, there are banks of tubes 20 extending between and suitably connected at their extremities in the tube plates 16 and 17, and similarly in the compartment B in the shell 10, there are banks of tubes 21 extending between and suitably connected at their extremities in the same tube plates 16 and 17. In the water bonnet 19 there is a condensate inlet connection 22, and in the same water bonnet there is a condensate outlet connection 23. The condensate inlet connection is connected by any suitable means to the condenser or other chamber from which the steam and air or other gases are to be drawn, and as will be understood, the condensate passes in through the condensate inlet connection 22 to the compartment *a* in the bonnet 19 and through the upper bank of tubes in the inter-heater to the compartment *b* in the bonnet 18, thence through the lower bank of tubes in the heater section of the inter-condenser to the compartment *c* in the bonnet 19 and thence to the condensate outlet connection 23 from which the condensate is conveyed to a second heater as hereinafter described. In the water bonnet 18, there is a circulating water inlet 26 and a circulating water

outlet 27. Cooling water from a suitable source is supplied to and through the circulating water inlet 26 to a compartment *d* in the water bonnet 18, thence through the upper bank of tubes in the compartment B to the chamber *e* in the water bonnet 19 and thence through the lower bank of tubes in the compartment B to the chamber *f* in the water bonnet 18 and thence to the circulating water outlet 27.

Together with the main heater or inter-condenser body hereinbefore described, I may also employ an auxiliary heater body 28 which is also preferably cylindrical and may be mounted on a suitable base 29. Also as illustrated in the drawing, the upper side of the auxiliary heater body may be provided with a reinforced cap 30 to receive and support the base 31 of the main heater body. In a suitable position in the side wall of the auxiliary heater body, there is a flanged boss 32 surrounding an opening in the wall of the auxiliary heater body, and adjacent the bottom of the auxiliary heater body there is a tapped opening 33 in which there is connected a drain pipe 34 having a vent 35 or stand pipe also associated therewith. It will be understood, however, that separate openings in the auxiliary heater body may be made for a vent pipe connection which is independent of the drain pipe connection, as such a construction is an obvious equivalent of that illustrated and described. The ends of the auxiliary heater body are also flanged and tube plates 36 and 37 are suitably connected thereto. At one end a water bonnet 38 is connected to the tube plate 36 and at the other end a water bonnet 39 is connected to the tube plate 37. Internally of the body of the auxiliary heater there is a bank of tubes 40 extending between the tube plates, and at their extremities suitably connected to the said tube plates. In the water bonnet 39 there is a condensate inlet 41 and connecting this inlet with the condensate outlet 23 in the water bonnet 19, there is a pipe 42. Similarly in the water bonnet 38 there is a condensate outlet 43. Together with the heater members hereinbefore described, I also employ steam jet ejectors for moving the mixture of steam and air or other gases from the condenser or other chamber to be evacuated. 44 indicates an expansion tube which at one end is flanged and secured to the boss 11 preferably at the top of the body of the main heater 10. Connected at the upper or outer end of the expansion tube 44 is an elbow 45. This elbow is fitted interiorly with a partition wall 46 in which there is mounted a steam jet expansion nozzle 47. Also between the nozzle 47 and the adjacent end of the expansion tube, I may employ a throat piece 48 into which the outer end of the expansion nozzle preferably extends. In

the elbow 45 there is also fitted a valve 49 for regulating the extent of the opening of the admission port in the expansion nozzle 47. Furthermore, one end of a steam pipe 50 is connected to the valve chamber in the elbow 45, while the other chamber therein is adapted to be connected to the condenser or other chamber to be evacuated.

As illustrated, I also employ a second elbow 51. This may be similar in all respects to the elbow 45 and is suitably connected to the boss 12 so that the compartment B communicates with one of the chambers in the elbow 51 provided therein by a partition wall 52. In this partition wall 80 there is an expansion nozzle 53, the outer or delivery end of which extends appreciably into the throat piece 54. The other end of the elbow 51 is connected to one end of the expansion tube 55, the other end of which 85 is connected to one side of an elbow 56, the opposite side of which is connected to the flanged boss 32 on the auxiliary heater body. A steam pipe 57 in which there is a suitable valve 58 is connected to the valve chamber in the elbow 51, the valve therein being the same as that disclosed in the elbow 45. As herein illustrated, I have shown a single expansion nozzle 47 in the primary stage of the operation of the apparatus and also a single expansion nozzle in the secondary stage of the operation of the apparatus. It will be understood that without departing from the nature and spirit of the invention a plurality of steam jet expansion nozzles may be employed either in the primary stage or the secondary stage or in both the primary and secondary stages, and furthermore that in the use of a plurality of nozzles in either stage when the diameter or bore of the nozzle is relatively small it is desirable to use a screen at the end of the steam supply pipe to prevent any particles which may be included in the steam from becoming engaged in the passages of the nozzle to obstruct the same and thus prevent the free passage of the steam therethrough.

In the use of this apparatus, steam is admitted through the pipe 57 to the valve chamber in the elbow 51, and from this valve chamber by way of the pipe 50 to the valve chamber in the elbow 45. From the valve chamber in the elbow 45 depending upon the position of the valve 49, steam is admitted through the expansion nozzle 47 into the expansion tube 44, and due to the velocity acquired by the expanding steam, the steam and air and other gases in communication with the other elbow compartment are carried along to the compartment A in the main heater body 10. These gases, together with the steam from the steam jet nozzle surround the banks of tubes in the compartment A and raise the temperature of the condensate which is conducted 130

through these tubes. At the same time steam is also admitted through the expansion nozzle of the ejector in the elbow 51 into the expansion tube 55 so that the velocity acquired by the expanding steam creates a vacuum in the compartment B and carries therefrom the air and other non-condensable gases which pass from the compartment A to the compartment B in which latter the steam and other condensable gases are condensed and carried to the drain pipe 15. The steam from the ejector nozzle in the elbow 51 and the air and other non-condensable gases from the chamber B are conducted through the expansion nozzle 55, the elbow 56 to the interior of the auxiliary heater body 28 surrounding the banks of tubes therein so as to enable the steam to further heat the condensate which is carried from the primary or main heater body by way of the pipe 42 to the interior, that is, through the tubes in the auxiliary heater body so as to be further heated therein before passing from the auxiliary heater by way of the condensate outlet 43 to be returned to the boiler or other heater or apparatus. Obviously, the steam from the interior of the auxiliary heater, together with the non-condensable vapors which pass from the chamber B in the primary heater are conveyed from the auxiliary heater by the drain pipe 34.

By reference to Figs. 3 and 4, it will be seen that instead of employing the main and auxiliary heaters as separate bodies, the same may be contained in a unitary structure. In thus carrying out the invention, I employ a shell or body member 59 in which there is a transverse partition wall 60 dividing the interior thereof into two separate compartments, the lower of which comprises the auxiliary heater compartment, while the upper comprises the main or primary heater compartment. In the upper compartment there is also a partition wall 61 extending from the upper wall of the body 59 to a line appreciably distant from the transverse partition wall 60. This vertical partition wall 61 divides the upper compartment into two compartments, one of which is a heater compartment, and the other the condenser compartment. In the heater compartment C there are banks of tubes 62, 63, 64 and 65, while in the condenser compartment D there are banks of tubes 66 and 67. Furthermore in the auxiliary heater compartment there are banks of tubes 68. All these banks of tubes extend between and at their extremities are suitably connected in the tube plates which are similar in all respects to those employed with the other form of the invention.

In the water bonnet 89 there is provided a condensate inlet 69 through which the condensate is conveyed to a chamber *g* and

thence to and through the upper bank of tubes 62 to a chamber *h* in the water bonnet 90; from the chamber *h* this condensate passes through the next lower bank of tubes 63 to a chamber *i* in the bonnet 89 from 70 which the condensate passes through the next successive lower bank of tubes 64 to a chamber *j* in the bonnet 90; from the chamber *j* the condensate passes through the bank of tubes 65 to the chamber *k* in the 75 bonnet 89. From the chamber *k* the condensate passes through the bank of tubes 68 in the auxiliary heating chamber to the condensate outlet connection 70 in the other water bonnet from which the heated condensate is conveyed to the boiler or other apparatus.

Similarly also in one of the water bonnets there is a circulating water inlet 71 and a 85 circulating water outlet 72 so that the circulating water may be passed through the former to and through the bank of tubes 67 and then to and through the bank of tubes 66 to the circulating water outlet 72 to provide condensing means in the chamber or 90 compartment D.

In this structure as in that hereinbefore described, steam from a suitable source is passed through a valve in the steam pipe 73 to the valve chamber in an elbow 81 and through a steam pipe 74 therefrom to the valve chamber in an elbow 75 which is connected to the main condenser or other chamber from which the air, steam and other gases are to be withdrawn. The elbow 75 is connected by an expansion tube 76 so as to provide communication between the valve inlet side in the elbow 75 to the compartment C in the heater so that the steam from the ejector in the elbow 75 is employed in 100 the compartment C to heat the condensate, the steam and gases passing into the compartment C through an inlet opening 77 in the top of the body of the heater. The steam and other condensable gases are 105 drawn from the compartment C to the compartment D by the steam passing through the ejector nozzle in the elbow 81 which is connected to the compartment D by an elbow 80 through an opening 79 in the upper wall of the heater and the steam and other condensable gases are condensed in the compartment D and conveyed away by the drain pipe 78, whereas the air and other non-condensable gases are carried along by the velocity acquired by the steam from the ejector in the elbow 81 and pass through the expansion tube 82 through the elbow 83 and an opening 84 in the side wall of the heater into the compartment in the auxiliary heater portion thereof so as to surround the banks of tubes 68 therein to further heat the condensate while the same is passing through these banks of tubes 68. The air, steam and other gases from the compartment

ment in the auxiliary part of the heater are conveyed away through a drain pipe 85 secured in a tapped opening 86 adjacent the bottom of the auxiliary heater compartment and as illustrated, the drain pipe 85 may be provided with a discharge pipe 87 and also with a vent or stand pipe 88.

From the foregoing, it will be apparent that in the use of the hereinbefore described 10 apparatus, the condensate is heated in the main or primary heater, and then is further heated by the steam from an ejector nozzle in the secondary heater, thus materially increasing the efficiency of a condensing plant 15 by permitting the condensate to be returned to the original heating apparatus at a relatively high temperature.

I claim as my invention:

1. In an apparatus of the class described, 20 an ejector for moving air and gas, a unitary body having a partition wall extending substantially horizontally across the same and a division wall extending downwardly a predetermined distance from the top thereof 25 of so as to divide the interior of the unitary body into three compartments comprising an intercondenser or initial heater, a condenser and a heater section, the said intercondenser or initial heater being separated 30 from the condenser section by the said division wall and the intercondenser or heater and condenser sections being separated from the heater section by the said horizontal wall, banks of tubes in the intercondenser or initial heater section for the passage of 35 condensate from a condenser, banks of tubes in the condenser section for the passage of

an independent circulating medium, and banks of tubes in the heater section connected to the banks of tubes in the intercondenser or initial heater section, and a second ejector connected to the outlet of the condenser section and discharging into the said heater section.

2. In an apparatus of the class described, 45 an ejector for moving air and gas, a unitary body having a partition wall extending substantially horizontally across the same and a division wall extending downwardly a predetermined distance from the top thereof 50 so as to divide the interior of the unitary body into three compartments comprising an intercondenser or initial heater, a condenser and a heater section, the said intercondenser or initial heater being separated 55 from the condenser section by the said division wall and the intercondenser or heater and condenser sections being separated from the heater section by the said horizontal wall, banks of tubes in the intercondenser or initial heater section for the passage of condensate from a condenser, banks of tubes in the condenser section for the passage of 60 an independent circulating medium, and banks of tubes in the heater section connected to the banks of tubes in the intercondenser or initial heater section, and a second ejector connected to the outlet of the condenser section and discharging into the said heater section, there being no condenser section associated with the said heater section.

Signed by me this 1st day of April, 1921.

E. RAYMOND GOODRICH.
